UNITED STATES PATENT OFFICE.

ELIZABETH CHESHIRE AND EDWARD CHESHIRE, OF CINCINNATI, OHIO.

NEEDLE.

SPECIFICATION forming part of Letters Patent No. 317,508, dated May 12, 1885.

Application filed May 19, 1884. (No model.)

To all whom it may concern:

Be it known that we, ELIZABETH CHESHIRE and EDWARD CHESHIRE, citizens of the United States, and residents of Cincinnati, in the county of Hamilton and State of Ohio, have invented a certain new and useful Improvement in Needles, of which the following is a specification.

Our invention relates to an improved needle, adapted for use more particularly in the book-sewing machine forming the subject-matter of an application for Letters Patent of the United States filed by us May 24, 1883, Serial No. 96,063.

Our invention consists of a channeled or grooved needle-bar bent in two lines, one portion being slightly arched and the other straight, the straight portion being at the point end of the needle containing the eye and bent at a definite obtuse angle to the other portion or body of said needle.

In the accompanying drawings, Figure 1 is a central longitudinal section of a needle embodying our invention, the view being taken on line x - x , Fig. 2. Fig. 3 is a plan view of the needle. Fig. 4 is a broken sectional elevation of parts of the feed-carriage and needle-frames of our book-sewing machine, to which the needle is especially adapted, showing the said feed-carriage and needle-frames at their meeting-point in the sewing position. Fig. 4 is a detail view of the needle, showing its point entering the fold of a signature, which is in its sewing position, with one leaf horizontal and the other perpendicular.

A represents the fastening-shank of the needle; B, the convex or upwardly-curved portion of the needle-bar, and C the depressed eye end or point, which is straight and arched at an obtuse angle to the arched portion or body B.

D represents a channel or groove along the upper convex face or periphery of the needle-bar, running from the shank to the eye in the point thereof. The object of thus channeling

the needle-bar is to provide a receptacle along the top of the needle for the twine, to prevent its dropping to either side to become entangled with the shuttle-thread previous to the proper interlooping operation.

50

E represents the needle-frame of the machine, to which the needle is secured by an eyebolt, e, which clamps the shank A.

55

F represents the feed-carriage provided with a toothed signature-supporting plate, G.

g represents either of the teeth of plate G.

H represents the shuttle, which may be of any suitable construction, but preferably pointed at both ends.

I represents the signature shown in position 60 for the sewing operation in Figs. 3 and 4.

i represents the signature-fold.

In the operation of the needle in connection with a signature to sew it, the bent or depressed eye end C enters the fold i, its dip being sufficient to prevent the point entering the leaves of the signature on either side the fold. Thus the danger of rupturing or defacing the leaves is obviated and the positive formation of the binding-loop is insured. The convex 70 portion or upward curve, B, of the needle places the lower edge thereof above the lower edges of the adjacent teeth g of the signature-supporting plate and out of the path of movement of the shuttle, thus avoiding any accidental collision of the shuttle points and the needle.

75 We claim—

A needle composed of a grooved bar bent in two lines, one of such lines, which is straight 80 and comprises the eye-pointed end of the needle, being bent at an obtuse angle to the other line, which is slightly arched outward and comprises the body of the needle, substantially as and for the purpose specified.

ELIZABETH CHESHIRE.
EDWARD CHESHIRE.
